UNITED STATES PATENT OFFICE.

THEODORE A. SUNDAL, OF TABER, ALBERTA, CANADA.

MARGIN-INDICATOR FOR TYPE-WRITERS.

1,161,422.

Specification of Letters Patent. Patented Nov. 23, 1915.

Application filed March 6, 1915. Serial No. 12,696.

To all whom it may concern:

Be it known that I, THEODORE A. SUNDAL, a citizen of the United States, and resident of Taber, in the Province of Alberta, Dominion of Canada, have invented certain new and useful Improvements in Margin-Indicators for Type-Writers, of which the following is the specification.

This invention relates to typewriters and the objects of the invention are to facilitate in determining the depth of the bottom margin, to render the indicator collapsible thereby occupying a minimum of space, to adapt the indicator for use on any typewriter at present in use and other objects which will be made clear hereafter, and it consists essentially of the improved construction of indicator particularly described in detail in the following specification and accompanying drawings forming part of the same.

In the drawings, Figure 1 is a perspective view of the back of the typewriter carriage showing the improved indicator mounted thereon. Fig. 2 is a perspective view of the front of the typewriter carriage showing the manner in which the paper engages with the indicator. Fig. 3 is a perspective view of the improved indicator.

Like characters of reference refer to like parts in the several figures.

Referring to the drawings, A represents the carriage of a typewriter and B the improved indicator mounted thereon, the said carriage being of any usual construction well known in the art it is deemed unnecessary to further describe the same.

In the embodiment illustrated the guard 1 is held in position by a spring controlled clip 2 mounted on the spindle 3 which is utilized in the present invention to carry the U-shaped bracket 4 which forms the support of the indicator B.

It is desirable that the U-shaped bracket 4 should be fixedly secured in position and to prevent downward sagging or rotation I provide offset stops 5 designed to engage with the carriage A. The bracket is further provided intermediate of its ends and on opposite sides thereof with upwardly extending arms 6 suitably secured thereto, on which arms the graduated rods 7 are pivotally mounted. These rods in the non-operative position are adapted to lie along the

upper edge of the bracket 4 while in the operative position they are rotated upwardly and retained in a position at substantially right angles to the said bracket by means of the interlocking spring clips 8 suitably mounted on the bracket 4 adjacent to the said upwardly extending arms.

The assembling of the indicator will be clearly understood from the foregoing description.

In the use of the device it will be clear that as the paper is being fed through the typewriter, the upper portion of the paper will engage with the rods 7 and the upper edge register with the graduations thereon. Since the lengths of different types of paper are standardized it is only necessary for the operator to glance at the graduations on the rods 7 with which the upper edge of the paper coincides to determine the depth of the margin at the bottom of the sheet.

From this description it will be seen that I have invented an indicator capable of being quickly mounted on any ordinary typewriter and which will clearly indicate the margin left at the bottom of the paper utilized on such machines.

As many changes could be made in the above construction and many apparently widely different embodiments of my invention, within the scope of the claim, constructed without departing from the spirit or scope thereof, it is intended that all matter contained in the accompanying specification and drawings shall be interpreted as illustrative and not in a limiting sense.

What I claim as my invention is:

The combination with a typewriter and with the carriage thereof, of a U-shaped bracket having offset stops adapted to engage therewith, graduated rods pivotally mounted on said bracket, and means for retaining the rods in an operative position comprising upstanding laterally curved arms secured to said bracket in proximity to said rods, and spring clips formed upon the ends of said arms.

In witness whereof I have hereunto set my hand in the presence of two witnesses.

THEODORE A. SUNDAL.
